UNITED STATES PATENT OFFICE.

LEO J. GRUBMAN, OF ERIE, PENNSYLVANIA, ASSIGNOR TO ERIE METAL PRODUCTS COMPANY, OF ERIE, PENNSYLVANIA, A CORPORATION OF PENNSYLVANIA.

CLOTHES-WASHER.

1,374,850.

Specification of Letters Patent. Patented Apr. 12, 1921.

Application filed February 6, 1920. Serial No. 356,634.

To all whom it may concern:

Be it known that I, LEO J. GRUBMAN, a citizen of the United States, residing at Erie, in the county of Erie and State of Pennsylvania, have invented new and useful Improvements in Clothes-Washers, of which the following is a specification.

This washer is designed to be used in the ordinary wash boiler and circulates in the 10 manner of a percolator, that is to say, has a chamber with an upstanding tube from which the liquid is discharged into the mass of clothes. Heretofore difficulty has been experienced in washers of this type in 15 the sealing of the chamber by the clothes against the return of liquid to the chamber. One of the objects of the present invention is to obviate this difficulty. Other objects are to improve the construction involving 20 the details hereinafter described and claimed.

The invention is illustrated in the accompanying drawings as follows:

Figure 1 shows a plan view of the washer. 25 Fig. 2 a section on the line 2—2 in Fig. 1. 1 marks the percolator tube which is preferably closed at the top and has laterally disposed openings 2 in several banks, and 3 the chamber. This is formed with a top 30 plate 4 and sides 5. The sides are corrugated forming ribs 6, the lower ends of which form openings 7 between them. The lower ends of the projections are bent upwardly at 8 to the plane of the lower edge 35 of the plate and an overhanging lip 9 is formed around the edge, the edge of this lip being preferably beaded at 10.

The ribs or corrugations strengthen the sides. This is particularly true where the 40 washer is formed of sheet metal as is the usual practice. The bottom ends of the ribs lift the edges slightly off the bottom of the boiler when in use so as to make a clear passage for the return flow of water

and the lip 9 tends to protect the openings 45 against sealing through the action of the clothes.

In a general way the device operates in the same manner as devices of this character now in use, that is to say, the water returning to the chamber is converted into steam rapidly enough to force the water through 50 the openings 2 and into the clothes and this circulation is continued so as to effect the washing of the clothes.

I prefer to form a projecting rib 11 on the tube to indicate the desired water level for the use of the device.

What I claim as new is:

1. A clothes washer comprising a percolating tube; and a chamber from which the tube extends, said chamber having depressed 60 projections along its edge forming openings permitting the ingress of water under said edge to the chamber, the edge being provided with an overhanging lip.

2. A clothes washer comprising a percolating tube; and a chamber from which the tube extends, said chamber being formed of sheet metal and having corrugated side 70 walls, the lower edges of which form depressed projections with intervening openings along the edge to the chamber, the side walls having an overhanging lip.

3. A clothes washer comprising a percolating tube; and a chamber from which the tube extends, said chamber being formed of sheet metal and having corrugated side 75 walls, the lower edges of which form depressed projections with intervening openings along the edge to the chamber, the side walls having an overhanging lip, the lower ends of the corrugations being upturned to 80 the plane of the lip making a continuous lip in one plane.

In testimony whereof I have hereunto set my hand.

LEO J. GRUBMAN.
